UNITED STATES PATENT OFFICE

ROBERT SCHOEPKE, OF JUNEAU, WISCONSIN

WINDOW FRAME

Application filed April 2, 1931. Serial No. 527,309.

This invention relates broadly to window frames, and the primary object of this invention is to improve upon and simplify that type of window frame wherein a portion of one window frame jamb may be readily removed or set back so that the sash may be removed entirely from the frame, or disposed at substantially right angles to the frame to facilitate painting the sash, or washing the pane of the window on both sides of the window.

Other objects and advantages of the invention will become apparent from a study of the following description taken in connection with the accompanying drawings wherein:

Figure 1 is a sectional elevational view of a portion of a window frame having my improvement associated therewith.

Figure 2 is a perspective view of an adjustable portion of the jamb constructed in accordance with the present invention.

Figure 3 is an elevational view thereof, the same being shown as applied to the window frame.

Figure 4 is a sectional elevational view viewing the adjustable portion of the jamb from the rear thereof.

Figure 5 is a cross sectional view taken substantially on the line 5—5 of Figure 3.

With reference more in detail to the drawings it will be seen that 5 indicates generally a conventional type of window frame having the upper and lower sashes 6 and 7 slidably mounted therein. The reference character 8 designates a jamb of the window frame.

According to the present invention, a lower portion of the jamb 8 is cut away to provide an opening 9 within which is located the adjustable part of the jamb embodying the features of the present invention. Said adjustable part may be formed of metal, wood or any other suitable material and comprises an elongated frame including a pair of spaced parallel side members 9 connected at their upper and lower ends by cross members 10 secured to adjacent portions of the jamb 8 by suitable fastening elements 11. Each of the members 10 intermediate its end is pressed outwardly as at 12 to provide a substantially

channel shaped stop to align with the intermediate stop 13 of the jamb.

A pair of upper and lower shafts 14 and 15 are supported between the sides 9 and the shaft 15 has crank arms 16 journaled in openings provided in the sides 9, while the shaft 14 has crank arms 17 extending through vertical slots provided in the sides 9.

Shafts 14 and 15 are journaled in bearings 18 provided on the inner face of a plate 19 that may be formed of metal or other suitable material. Plate 19 intermediate its end is pressed outwardly to provide a longitudinally extending stop 20 that is channel shaped in cross section and is adapted to align with the stop 13. Plate 19 is normally positioned between the sides 9 with the upper end of its stop 20 received in the channel portion of the stop 12 of the upper member 10,

and the upper portion of the stop section 12 of the lower member 10 received in the lower channel portion of the stop 20 (see Figure 2).

As shown in Figure 5, one of the side members 9 is provided with a longitudinal channel 21 and one longitudinal edge of plate 9 is bent at right angles to the plate to provide a flange 22 adapted to engage the channel 21 when the plate 19 is so positioned in the frame as to have its stop 20 in alignment with the stop 13 for accommodating the sashes 6 and 7 to permit vertical sliding movement of the sashes in the usual manner.

When the parts are in the position shown in Figure 1, that is with the plate 19 in position to complete the jamb 8, the interlocking connection between stop 20 and the stop sections 12 of the members 10 serve to retain the plate in position against casual displacement.

When it is desired, for any reason, such as for painting the sash, or washing the outside of the panes of either of the sashes 6 or 7, the particular sash is moved to a position opposite the opening 9, as for example to that position of the lower sash 7 as shown in Figure 1.

The upper portion of the stop 20 may then be grasped by the hand and an upward push then exerted on the plate 9 thus rotating shafts 14 and 15 which serve to move the plate 19 inwardly with respect to the jamb

8 to assume the dotted line position suggested in Figure 1. The window sash may then be moved into a position directly opposite the opening 9 and then moved slightly through 5 the opening subsequent to removing the sash from the window frame or disposing it at right angles thereto to facilitate cleaning or painting of the sash.

Even though I have herein shown and 10 described the preferred embodiment of the invention, it is to be understood that the same is susceptible of changes, modifications and improvements coming within the scope of the appended claims.

15 Having thus described my invention, what I wish to claim as new is:

1. A window frame including in combination a jamb provided with an opening, upper and lower members transversely disposed relative to the jamb in operative position to said opening, each of said members provided with a vertical rib adapted to substantially aline with the window stop of said jamb and a plate for disposition between said members 20 and provided with a longitudinally extending rib adapted to aline with said rib to form a continuation of the window stop.

2. A window frame including in combination a jamb having an opening therein, a frame mounted in operative position with respect to the opening and including vertical side members and horizontal upper and lower cross members connecting the side members, each of said cross members provided with a 35 rib adapted to substantially aline with the window stop of the jamb, a plate, means for mounting said plate in the frame for movement relative to the jamb and said plate provided with a longitudinally extending rib 40 adapted to aline with the first mentioned rib to form a continuation of the stop.

3. A window frame including in combination a jamb having an opening therein, a frame mounted in operative position with respect to the opening and including vertical side members and horizontal upper and lower cross members connecting the side members, each of said cross members provided with a rib adapted to substantially aline with the 45 window stop of the jamb, a plate, means for mounting said plate in the frame for movement relative to the jamb and said plate provided with a longitudinally extending rib 50 adapted to aline with the first mentioned rib to form a continuation of the stop, and means 55 for retaining said plate in position within said frame against casual displacement.

4. A window frame including in combination a jamb having an opening, a frame 60 mounted in operative position with respect to said opening, a plate, means for mounting said plate within said frame for movement into and out of operative position with respect to said jamb, said plate provided with a longitudinally extending rib adapted to 65

aline with the window stop of the jamb to form a continuation thereof, and said frame provided with a side member having a longitudinally extending channel, and said plate provided with a flange engageable with said channel for yieldably retaining said plate within the confines of said frame. 70

5. A window frame comprising in combination a jamb including a relatively fixed frame having upper and lower members each of which has an intermediate portion pressed laterally to provide a window stop section, a plate, means for mounting the plate in the frame for movement relative to the frame, said plate having an intermediate portion thereof pressed outwardly to provide a stop section elongated longitudinally of the plate to substantially aline with the first mentioned stop sections when the plate is arranged within the frame. 80

6. A window frame comprising in combination a jamb including a relatively fixed frame having upper and lower members each of which has an intermediate portion pressed laterally to provide a window stop section, a plate, means for mounting the plate in the frame for movement relative to the frame, said plate having an intermediate portion thereof pressed outwardly to provide a stop section elongated longitudinally of the plate to substantially aline with the first mentioned stop sections when the plate is arranged within the frame, and all of said stop sections being substantially channel shaped in cross section and adapted to frictionally engage one with the other for yieldably retaining said plate in the last named position. 85 90

7. A window jamb including in combination a pair of upper and lower relatively fixed members each of which has an intermediate portion thereof pressed outwardly to provide a window stop substantially channel shaped in cross section, and a plate swingably mounted between said upper and lower members for movement relative thereto and having a portion thereof pressed outwardly to provide a window stop elongated longitudinally of the plate and channel shaped in cross section, said last named window stop adapted to receive in the channel thereof, proximate end portions of the first named stops when the plate is arranged in substantial alinement with said upper and lower members. 100 105 110 115

In testimony whereof I affix my signature. 120
ROBERT SCHOEPKE.
